United States Patent Office

Des. 197,655
Patented Mar. 10, 1964

197,655

TOY BUILDING SET UNIT

James O. Kuhn, Cincinnati, Ohio, assignor to Kenner
Products Company, Cincinnati, Ohio, a corporation of
Delaware

Filed Sept. 24, 1962, Ser. No. 71,823

Term of patent 14 years

(Cl. D34—15)

Fig. 1

Fig. 2

FIGURE 1 is a side elevational view of a toy building set unit showing my new design, the opposite side being substantially similar in appearance.

FIGURE 2 is a perspective view showing the unit disassembled.

FIGURE 3 is an exploded cross sectional view.

I claim:

The ornamental design for a toy building set unit, substantially as shown and described.
